UNITED STATES PATENT OFFICE.

HENRY G. BRANDWEIN, OF CHICAGO, ILLINOIS.

MATTRESS-FILLING MECHANISM.

Application filed December 10, 1923. Serial No. 679,673.

My invention relates to improvements in mattress filling mechanisms, and particularly to a device adapted for filling mattresses having inner tufting or compartments or sections therein, the filling material being inserted after the tufting of the mattress is already made or the compartments formed.

The invention has among its objects the production of an apparatus of the kind described which is simple, compact, durable, efficient and satisfactory for use wherever found applicable.

It has particularly as an object the production of a mattress making machine of the kind described that will be rapid in operation and will operate without injury or stretching of the mattress ticking or covering when filling inner tufted or compartment mattresses.

Many other objects and advantages of the construction herein shown and described will be obvious to those skilled in the art from the disclosures herein given.

To this end my invention consists in the novel construction, arrangement and combination of parts herein shown and described, and more particularly pointed out in the claims.

In the drawings, wherein like reference characters indicate like or corresponding parts:

Fig. 1 is a top plan view of the device showing some of the molds in place within a mattress casing;

Fig. 2 is a side elevation of the device;

Fig. 3 is a section taken substantially on line 3—3 of Fig. 2;

Fig. 4 is a section taken substantially on line 4—4 of Fig. 1;

Fig. 5 is a section taken substantially on line 5—5 of Fig. 1;

Fig. 6 is an enlarged fragmentary section showing locked filled mattress within the mattress casing;

Fig. 7 is a section taken substantially on line 7—7 of Fig. 6;

Fig. 8 is a section showing a modified form of charge stiffening stick; and

Fig. 9 shows a modified form of device.

Referring to the drawings, 1 indicates a table of any suitable size and height and adapted to accommodate a mattress. The mattress cover or tick 2 consists of the usual box-shaped bag or casing, in which upper

and lower sheets are connected together,

preferably at intervals so as to provide an inner tufting; or these sheets may be connected together by partitions, forming compartments. Obviously, the whole mattress might be a single compartment and the filling may be inserted therein in sections, even though the mattress may be tufted later.

The present apparatus is intended to fill the mattress and permit the easy insertion of one or more sections of filling material, regardless of the mattress construction itself. The filling material, which may be either of felt, kapok, cotton, hair or any suitable material for the purpose, is compressed in suitable molds of the desired size and shape. These molds have been very clearly described and specifically explained in my prior application, Serial No. 571,657, filed June 29, 1922, and each consists preferably of sections 3 and 4 removably hinged together at one end as indicated at 6 and having locking means 5 at its other end to hold the charge of filling material firmly compressed in place while handling the mold.

Handles 7 are provided for tripping or releasing the mold sections after they have been inserted into the mattress casing, thereby partially relieving the compression of the mold sections on the charge and permitting the ejection or removal of the charge from the mold.

Plungers 8 are slidably arranged within the molds and are adapted to bear against one end of the charge 9 therein. Obviously, when the plunger is actuated relative to the mold after the mold sections have been released from interconnection either by moving the mold or moving the plunger and tick, the charge will be ejected from the mold. In the machine illustrated, the plungers and tick are moved while the molds are held.

A stiffener or reinforcing stick 10 is generally arranged lengthwise of the mold so as to prevent any buckling or lengthwise compressing of the charge. This stiffener stick is moved together with the plunger and charge and may be removed from the mattress after the mold itself has been removed therefrom. In order to trip or release all of the locked molds in unison, I have arranged a latch 11 engageable with the handles 7, these latches being mounted upon bent levers 12, which may be operated by a foot lever 13.

In order to hold the mattress casing or

tick upon the table, a top frame 14 is fixed to extend across and above the table, there being pins or other fastening means 15 carried thereby and upon which the top sheet 6 of the casing may be releasably caught. The bottom sheet of the casing is adapted to be gripped or clamped across its free edge, as by a part 16, shown more clearly in Fig. 6.

Projecting upwardly from and movable with the part 16 which extends transversely across the table are actuating pins 17 engageable with projecting portions of the plungers 8. Projecting downwardly from the part 16 are pins 18 which connect the part 16 rigidly with a bar 19 extending transversely across the table parallel to and below the part 16.

Guide rollers 20 and 21 are spaced apart lengthwise of the table and are carried by the bar 19, these rollers engaging fixed guides 22 extending longitudinally of the table. A belt 23 has one end connected or clamped to the part 16, the other end of said belt passing over a winding pulley 24. A sprocket chain 25 has lugs 26 adapted to engage the angle bar 19 and push it longitudinally of the table when the sprocket chain is driven. Obviously there may be any number of chains and cooperating parts. The winding drum 24 and the sprocket chain 25 are interconnected by a chain 27 so that these mechanisms are driven in unison. A drive gear 28 meshes with one of the sprockets driving the chain 25, this drive gear being operatively connected with so as to rotate or drive pressure rollers 29 mounted adjacent the rear end of the table, as shown more particularly in Fig. 2. These rollers are shown substantially adjacent the ends of the molds, it being understood that they may be at such point as desired to perform their functions. Their location depends on their height from the table. Variations in height or location, of course, vary their actions on the molds, and the desired mold action may depend on the mattress construction, length of tufting, etc.

Additional pressure rollers 30 are spaced from the pressure roller 29, these latter rolls being spring-pressed as at 31. The operation of the device is as follows:

The mattress casing or tick is arranged on the table and its upper and lower free edges are secured to the fastening pins 15 and the part 16, respectively. All of the filled locked molds are then inserted into the casing from the open end, the handles 7 of molds being caught over the levers 11. The foot pedal is then operated so as to move the mold sections and release or unlock the sections of all of the molds in unison, causing these sections to move apart or separate on account of the high compression of the charge therewithin, and as shown more particularly in Fig. 2, the top and bottom

of the molds engage against the top and bottom sheets of the casing. The free edge of the top sheet is then released from its fastening pins on the frame 14 and the drive mechanism is started up so that the lugs 26 or the sprocket chains 25 push against the angle iron 19, which, in turn, causes the pins 17 to push or press against the plungers 8, moving all of said plungers (as shown in Fig. 4) to the left to eject the charges from the molds. At the same time, the belt 23, which supports the mattress, carries the casing away from the molds, the molds having abutments, or stops 32 thereon, which engage against the edge of the table to prevent their movement. Thus the mattress is both pulled and pushed from the molds at its open end.

In addition to this, the rollers 29, which are driven in unison with the belt and chain, frictionally engage the top of the mattress and tend to move or withdraw the same from the molds and hold the molds against excessive opening with resultant strain on the ticking or tufting. If desired, the periphery of the rolls 29 and 30 may be suitably covered so as to increase their pull on the mattress. After the mattress has passed under the roll 29, it is engaged by the rolls 30.

Thus it is seen that there are several devices, acting coordinately to engage the mattress and insure that it will be uniformly and positively withdrawn from the mold, these withdrawing means being the rolls 29 and 30, the belt 23, and the pins 17.

After the mattress has been withdrawn completely from the mold, the stiffening sticks 10 may be removed therefrom and the mattress then conveyed to a suitable machine for sewing up or closing the open end of the same. In Fig. 8 there is shown a modified form of stiffener stick, the same having been described in my prior application before mentioned, and in which vanes 32^a are provided, the same being collapsible against the body of the stick when the stick is withdrawn from the charge.

In Fig. 9 the drive mechanism is slightly modified. 33 indicates the drive shaft having a gear thereon which meshes with a gear 34 to drive the roller 29, said first-mentioned gear also meshing with a gear 35 on a shaft 36. A gear 37 is arranged on the shaft 36 and meshes with gears 38 and 39, the former driving the pressure rolls 30 and the latter driving a lead screw 40. The lead screw 40 is extended through a threaded sleeve 41 having a lug 26 thereon to engage against the angle iron 19 carried by the pins 17.

The machine described is particularly adapted for the filling of mattresses provided with an inner tufting in the form of straps or the equivalent arranged in the inside of the mattress before filling, or for compartment mattresses in which the sections are

separated by partitions or the like. By filling all of the compartments or sections at one time or simultaneously there is no undue strain on the ticking, thereby stretching or tearing the same. The work is more uniform in appearance, and production is speeded up.

Having thus described my invention, it is obvious that various immaterial modifications 10 may be made in the same without departing from the spirit of my invention; hence I do not wish to be understood as limiting myself to the exact form, construction, arrangement and combination of parts herein shown 15 and described or uses mentioned.

What I claim as new and desire to secure by Letters Patent is:

1. In a mechanism of the character described, a belt adapted to support a mattress 20 casing open at one end and with a filled locked mold inserted in the casing, a friction roller engageable with the casing to move it away from the mold, means for securing the casing to the belt, winding means engageable with the belt and drive means for actuating said winding means.

2. A mechanism of the kind described comprising a table for carrying a mattress ticking open at one end, molds adapted to be 30 filled with filling material and inserted in said ticking and having movable plungers therein, means for withdrawing said ticking from said molds, and means connected to said last-mentioned means for actuating said plungers to eject material from the molds during said withdrawal of the mattress ticking.

3. In a mechanism of the kind described, a frame, mattress-supporting means mounted 40 on the frame, a mold for releasably holding filling material in a mattress ticking carried by the mattress-supporting means, a plunger in the mold, means for causing relative motion between the mattress-supporting means and the frame and for causing relative motion between the plunger and the frame, and means for limiting relative motion between the mold and the frame.

4. A mechanism of the kind described comprising a table adapted to support a mattress 50 thereon, means for filling said mattress, and rollers engageable with said mattress to withdraw it from said filling means.

5. A mechanism of the kind described comprising a table for supporting a mattress ticking and a filled mold thereon, a lock for the mold, means for moving said casing and mold relatively of one another to eject the material from the mold into said ticking 60 during said movement and means actuated by the last mentioned means for unlocking the mold during the initial portion of said movement.

6. A mattress stuffing mechanism comprising 65 a table adapted to support a mattress

thereon with a filled sectional mold inserted into said mattress, a roller engageable with said mattress adjacent the rear of said mold to limit the separation of the mold and to withdraw the mattress from the mold, and 70 means for rotating the roller.

7. A mechanism of the kind described comprising a table arranged to support a mattress ticking thereon, a plurality of detachably connected compressed filled molds 75 insertable into said ticking, and means rotatably engageable with said ticking adjacent the rear of all of said molds to limit the separation of the molds.

8. In a mattress stuffing mechanism, means 80 arranged to receive a mattress ticking thereon with locked molds inserted into said ticking, means for simultaneously unlocking all of said molds, means for moving said ticking and molds relatively of one another, and 85 pins operably connected to said last-mentioned means to empty said molds during said relative movement.

9. A mechanism of the kind described comprising a table adapted to receive a mattress 90 casing thereon and locked molds inserted into said casing and having ejecting means therein, means for unlocking all of said molds in unison, driven rollers engageable with said mattress for pulling it relative to said molds, and means operably connected to said rollers and actuated in unison therewith to engage said ejecting means to empty said molds during the withdrawal of said casing.

10. A mechanism of the kind described comprising a movable belt adapted to support a mattress casing with a locked and filled mold inserted into the casing, means for securing one end of the casing to the belt, winding means engageable with the 105 belt, means for unlocking the mold after it has been inserted into the casing, a plunger in the mold, and drive means operatively connected to the winding means for winding the belt and for moving the plunger to eject 110 the filling material from the mold.

11. In a mechanism of the kind described, a belt adapted to support a mattress casing open at one end and with a filled locked mold inserted in the casing, said mold having 115 a plunger therein, means for unlocking the mold so that the pressure on the filling material is relieved, a friction roller engageable with the casing to move it away from the mold, pins engageable with the plunger, guide 120 means for the pins, means for securing the casing to the belt, winding means engageable with the belt, and drive means for actuating said winding means, pins and pressure roll in unison.

12. A mechanism of the kind described comprising a belt adapted to support a mattress casing with a filled mold inserted in the casing, means for securing the casing to the belt, and means for winding up the belt to 130

withdraw the casing and the filling material from the mold.

13. A mechanism of the kind described comprising a belt adapted to support a mat-
tress casing with a filled mold inserted in the
casing, the mold having a plunger therein,
means for securing the casing to the belt,

and means including means for winding the
belt for moving the casing and plunger rela-
tive to the mold.

10 In testimony whereof, I have hereunto
signed my name.

HENRY G. BRANDWEIN.
